(57) **CLAIM**

The ornamental design for an applicator refill, as shown and described.

DESCRIPTION

The nature of this product is an applicator refill used in an applicator for applying cleaning gel and/or disinfecting and/or fragrancing adhesive gel to the inside surface of a toilet bowl.

FIG. 1 is a top, front, right, perspective view of an applicator refill embodying our new design;

FIG. 2 is a top, rear, left, perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines shown in the drawings are for illustrative purposes only and form no part of the claimed design.
